UNITED STATES PATENT OFFICE.

HENRY SIMON, OF PROVIDENCE, RHODE ISLAND.

SHIRT-STUD AND SLEEVE-BUTTON.

Specification forming part of Letters Patent No. 37,777, dated February 24, 1863.

To all whom it may concern:

Be it known that I, HENRY SIMON, of the city and county of Providence, in the State of Rhode Island, have invented a new and useful Improvement in Studs, Sleeve-Buttons, and similar articles; and I do hereby declare that the following specification, taken in connection with the drawings, making a part of the same, is a full, clear, and exact description thereof.

Figures 1, 2, 3, and 4 are views of one variety of shirt-stud. Figs. 5, 6, 7, and 8 are views of another style.

The object of my invention is to produce articles of this character more economically than heretofore, both in respect to the quantity of precious metal employed and in the amount of manual labor required, while at the same time the appearance of the article and its strength and durability are not impaired, and which also has the advantage of not crocking or soiling the linen when worn. It has heretofore been the practice to construct these articles either from thick metal or from disks of thin sheet metal soldered at the edge, and the space within filled with solder or some base metal, in order to obtain the degree of strength which the article requires. If stock therefore of a high grade is used the expense is correspondingly increased, while, on the other hand, if a poor quality of gold is used the article is inferior as one of ornament and of little durability. Again, if thin disks of metal are used, and the space between them filled with solder, the increased cost of manufacture nearly compensates for the amount of gold saved.

I make my improved stud or sleeve-button as follows: I strike up a single disk for the faces of the stud or button of thin sheet metal, using only one disk if the stud is of the variety shown in Fig. 2, and two disks only if it be a double-faced stud, as shown in Fig. 8. Although I do not limit myself to the use of gold for these disks, yet this metal should be employed, as the amount of stock required for the purpose is exceedingly small, the plate not requiring to be any thicker than a sheet of the thinnest paper. These faces should be struck with a turned or cup-formed edge, for

the purpose of receiving the backing which I employ.

Having obtained the shell by any of the modes of manufacture employed, I first coat the inside with solder and then flow upon it—filling the back flush with the edge of the shell—a surface of enamel. This enamel is composed of any of the cheap compounds of which this material is made, the most usual being silex, borax, and an oxide of one of the metals. The composition is placed upon the back of the shell with a brush, and then is subjected to a heat sufficient to produce liquefaction. After the enamel has become cooled the stud or button shows on one side the face of the metal only, and upon the other side the surface of enamel only.

I have described only the process of making the faces of the stud, but it must be understood that the bar of metal which holds the two faces together, or the coil which acts in place of the second face, Fig. 1, is attached to the disk by solder before enameling by solder in the usual way.

Besides the obvious advantages which I gain both in economy of labor and of material used over any of the methods now employed, it is clear that this description of stud or button will not soil the linen, from the fact that its inner face is of a material which leaves no crock like that which comes from gold. In point of strength and durability, too, it is fully equal to the strongest article of the kind now made.

I do not limit myself to any form of stud or button, my improvement being applicable to any of the forms in use.

What I do claim as my invention, and desire to secure by Letters Patent, is—

The improved stud or button described, composed of a shell of sheet metal with a backing of enamel, the whole article being substantially such as specified.

In witness whereof I have hereunto set my hand this 24th day of December, A. D. 1862.

HENRY SIMON.
